ABSTRACT: A device for inserting fastening elements into solid material covered by a compressible material such as an insulating material, and comprised of a tubular member arranged to extend through the compressible material and having a first end in contact with the face of the solid material and a second end adapted to extend outwardly from the outer surface of the compressible material. A platelike support member having an opening therethrough is attached to the second end of the tubular member and means for driving the fastening elements are supported on the support member aligned with the tubular element for inserting the fastening elements into the solid material. The support member is provided with a handle portion for holding it in place while the fastening elements are inserted into the solid material.

A wall construction comprising a wall of solid material having a coating of a compressible material secured to and extending from its face and a coating covering the compressible material. The coating is secured to support members attached to fastening elements which extend through the compressible material and are secured to the wall of solid material. The coating material is supported by the fastening elements secured into the wall of solid material and does not compress or otherwise damage the underlying layer of compressible material.

MEANS FOR DRIVING FASTENING ELEMENTS INTO
SOLID MATERIAL COVERED BY A COMPRESSIBLE
MATERIAL

This is a division of application Ser. No. 676,184 filed Oct. 18, 1967, and now Pat. No. 3,487,533, issued Jan. 6, 1970.

SUMMARY OF THE INVENTION

The present invention is directed to an apparatus for driving fastening elements into a solid material covered by a compressible material, such as the various fibrous insulating materials, and in addition, to an arrangement for supporting a coating over the compressible material without compressing or otherwise damaging it.

The term "compressible material" as used herein is deemed to refer to pressure-sensitive material, to wit, material which is negatively affected by the application of pressure. The material may thus be disintegrated by pressure. The term does not include materials wherein the effect is reversible, to wit, materials which, once the pressure action has been discontinued, revert to a state or condition which they had before the pressure was applied.

In the building construction industry, solid materials, such as masonry and concrete walls, are provided with a layer of insulating material and an additional outer layer or coat is provided over the insulating material. Various insulating materials, such as fiberglass, rock wool and the like, may be used to cover the concrete wall. However, though the composition of these materials is different, they are similar in that they are of an easily compressible construction. When such insulating materials are exposed to pressure, they have a tendency to be compacted or compressed and the insulating capacity of the material is diminished if not completely destroyed. Further, the insulating material is incapable of supporting the coating which covers it so that the outer coat must be supported from the wall backing the compressible insulating material. Generally, the outer coat is applied to a metal screen which, in turn, must be supported either directly or indirectly from the concrete wall. In placing the outer coat over the insulating material, it must be placed in such a manner that the insulating material is not compressed or otherwise damaged.

The present invention is directed to the problem of covering a compressible material secured to a solid material base whereby the outer coat is supported by the base material and the compressible material is not altered in shape or composition whereby its usefulness would be impaired. Further, the invention is concerned with an arrangement for placing the outer layer in place which is simple to perform and can be carried out in an expeditious manner.

The primary object of the present invention is to provide a means for coating the outer surface of a compressible material secured to a solid material base without compacting or otherwise altering the formation of the compressible material.

Another object of the invention is to afford a device for inserting fastening elements into the solid material base without disturbing the compressible material.

Still another object of the invention is to provide a device for inserting the fastening elements into the solid material base which is easy to handle and operate.

Yet, another object of the invention is to afford a wall construction comprising a solid material base covered by a compressible material which, in turn, is covered by an outer coat supported by the solid material, the outer covering being secured to the base whereby it does not compact the compressible material.

Accordingly, in the present invention, a compressible material, such as a fibrous insulating material, is secured to a solid material base, such as a concrete wall, and fastening elements are inserted through the compressible material into the solid material base for supporting a covering over the compressible material. Preferably, openings are afforded in the compressible material through which the fastening elements are inserted into the solid material base. By providing such openings, there is not likely to be any damage caused to the compressible material during the insertion of the fastening elements.

In inserting the fastening elements, a member is provided for supporting the fastening element inserting tool during the inserting operation. This support member is supported off the solid base material to prevent the transmission of pressure to the compressible material when the fastening elements are driven into the base. Moreover, since the inserting tool must be forced against a nonyielding surface before it can be fired, the support member permits the step to be carried out without any force being exerted against the compressible material. Additionally, the support plate can absorb any excess energy supplied by the inserting tool when the fastening elements are driven into the solid material base.

As mentioned previously, the compressible material may have openings or holes through it, extending from its outer surface to the solid material base, and these openings serve to receive bearing members extending between the support plate and the solid material base.

In a preferred embodiment of the invention, a tubular member or bushing forms a part of the support plate extending from it into contact with the solid material base. In addition to providing supporting means for the support plate, the tubular member also serves as a guide for the insertion of the fastening element and for the inserting tool during the driving operation. The tubular element is of particular advantage when thick layers of compressible insulating material are placed on the surface of the solid material base. In addition, the tubular member may have a short extension beyond the face of the plate to which the inserting tool is applied for properly aligning the inserting tool. Further, for ease in inserting the fastening elements, a handle is provided on the support plate.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWINGS

In the Drawings:

FIG. 1 is a side view, partly in section, of a device embodying the present invention for inserting fastening elements into a solid material base;

FIG. 2 is a front view of the support plate of the device shown in FIG. 1; and

FIG. 3 is a sectional side view showing a number of fastening elements extending into a solid base material through a compressible material and supporting an outer coat.

DETAILED DESCRIPTION

In FIGS. 1 and 3, a solid wall 1, such as concrete, has a layer 55 of compressible insulating material 2 secured to its face. The insulating material 2, which may be Fiberglass or a similar easily compressible insulating material, is fastened to the wall as by gluing. The insulating effect of the material 2 is relatively easily destroyed if the material is compressed or compacted 60 against the concrete wall 1. Further, because the insulating material has no structural strength in itself, it cannot support a finishing layer or coat on its outer surface. Moreover, any application of another coat directly to the surface of the insulating material 2 would damage it and is likely to cause it to be stripped from the wall. Accordingly, in FIG. 1 a device is shown for inserting fastening elements into the solid material base 1 without damaging or compacting the insulating material 2. In preparing the insulating material for application to the wall, a number of openings 5 are provided through it for ease 65 in inserting the fastening elements at specific locations. With the openings 5 formed through the insulating material, there is less likelihood of damage to the insulating layer during the insertion of the fastening elements.

In the device A a tubular member 7 has a first end 7 a bearing 75 against the surface of the solid base material 1 and a

second end 7b located outwardly from the outer surface of the insulating material 2. Extending substantially perpendicularly to the tubular member 7 is a support plate 8 having a centrally arranged opening 8a through which the tubular member extends. The support plate 8 is positioned in substantially parallel relationship with the surface of the solid base material 1 and is spaced closely from the outer surface of the insulating layer 2. The tubular member 7 and support plate 8 are integrally secured together by the weldment 10. A short extension 11 os the tubular member 7 extends through the support plate 8 and affords a centering means for an inserting tool 12 shown in phantom in FIG. 1. When the inserting tool 12 is activated by depressing it against the support plate for driving a fastening element into the solid material base, the support plate rests, if at all, only lightly against the insulating material and does not compact or otherwise damage it.

At the lower end of the support plate a right angle section 13, 14 extends from the plate outwardly away from the surface of the insulating material so that the support plate can be easily handled during the step of inserting the fastening elements. In FIG. 2, the plate 8 is shown with the handle at its lower end and the extension 11 of the tubular member extending through the plate, it will be appreciated that the handle can be located at different positions on the plate for the convenience of the person using it.

After a fastening element is inserted through the insulating material into the solid material base, the inserting tool 12, and the support plate 8 and its integrally attached tubular member 7 are removed and can be used in inserting the next fastening element.

In FIG. 3, a section of the composite wall is shown comprising the inner solid base material 1, the compressible insulating layer 2 and the outer coat 3. In constructing the composite wall after the fastening elements are in place, a wire screen 4 is supported over the ends of the fastening elements which extend outwardly beyond the surface of the insulating layer 2. The screen is attached to the fastening elements with clamps or other means well known in the art, and a coating, such as a plaster or mortar, is applied to the screen 4. The outer coat or covering layer 3 is supported by the screen which, in turn, is supported on the fastening elements 6. The fastening elements extend through the insulating material and are supported in a cantilevered manner from the solid material base 1. In this arrangement, the insulating layer is properly covered, and it is

protected from compaction or other damage to its form.

While a specific embodiment of the invention has been shown and described in detail to illustrate the application of the inventive principles, it will be understood that the invention 5 may be embodied otherwise without departing from such principles.

I claim:

1. A device for inserting fastening elements into a solid material covered by a compressible material comprising a support member arranged to be spaced from the solid material, and means extending between said support member and said solid material for maintaining said support member in spaced relationship with the solid material and in not greater than lightly contacting relationship with the compressible material, 10 said support member having an opening therethrough whereby fastening elements can be driven through the opening into the solid material.

2. A device, as set forth in claim 1, wherein said support member comprises a plate arranged in substantially parallel relationship with said solid material and with the opening in said support member spaced inwardly from the edges of said plate and disposed substantially centrally between at least one pair of oppositely disposed edges thereof.

3. A device, as set forth in claim 1, wherein said means extending between said support member and the solid material comprises a tubular member having a first end in contact with the solid material and a second end extending through the opening in said support plate.

4. A device, as set forth in claim 3, wherein said tubular member and said plate are integrally secured together.

5. A device, as set forth in claim 4, wherein said tubular member is disposed substantially normally to said plate and the second end of said tubular member extends through said plate and is spaced outwardly from the surface of said plate remote from the surface of the solid material.

6. A device, as set forth in claim 5, wherein a handle is formed on said plate and is adapted for holding the plate while fastening elements are driven through said plate and tubular member into the solid material.

7. A device, as set forth in claim 6, wherein said handle comprises an edge portion of said plate bent in a generally right angle configuration extending outwardly from said plate in the direction of the second end of said tubular member.
